UNITED STATES PATENT OFFICE.

JOHN GABRIAL, OF BROOKLYN, NEW YORK.

CONVERTIBLE WINDOW-CLEANER'S STAND.

1,402,156.

Specification of Letters Patent. Patented Jan. 3, 1922.

Application filed March 9, 1921. Serial No. 451,015.

To all whom it may concern:

Be it known that I, JOHN GABRIAL, citizen of Hungary, and resident of Brooklyn, in the county of Kings and State of New York, have invented certain new and useful Improvements in Convertible Window-Cleaners' Stands, of which the following is a specification.

This invention relates to a convertible window cleaner's stand which may be secured to the window frame exteriorly to the window when the latter is to be washed, and may be converted into a chair at other times.

15 The invention has for an object to provide a simple and inexpensive device of this sort which may be readily secured to or detached from the window frame and will provide a convenient standing place for the person 20 washing the window, and also adequately guard such person against falling.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of my improved stand in position on a window.

Fig. 2 is an elevation of the lower portion thereof, viewed as indicated by the line 2—2 of Fig. 1.

35 Fig. 3 is a front view of the device as arranged to form a chair.

Fig. 4 is a side view thereof.

Fig. 5 is a fragmentary horizontal section showing the means employed for clamping 40 the stand to the window frame.

As here embodied my improved device comprises an open topped box-like member, indicated generally at 10. This member preferably consists of a frame made up of 45 the rectangular bottom frame element 11, the posts 12 extending upwardly from the corners thereof, and a rail element 13 extending around three sides thereof at the top. To this frame is secured a solid floor 50 14 and a series of wire panels comprising end panels 15, and side panels 16 and 17 respectively, the panels 15 and 16 being rigidly secured to the frame, while the panel

17 is removable as will be later set forth, 55 this panel being located on the outer side of the frame, along which the rail 13 does not

extend. The posts 12 on this side of the frame are vertically grooved on their inner faces as at 18 to slidably receive the frame 17 of the panel 17, which is removed from 60 this position when the device is converted into a chair.

This box-like member 10 forms the main body of my improved stand and is adapted to be secured on the window frame as follows: Upon opposite ends of the stand the rail element 13 is formed with extensions 20 which project over and rest upon the sill 21 of the window. These extensions are longitudinally slotted as at 22 to receive pins 70 23 carried by rigid arms 24 projecting from the upper corners of a rectangular clamp member 25 which is adapted to engage the inside of the window sill. These arms 24 project over the sill 21 adjacent to the rail 75 extensions 20 which they overlap, the overlapping portions of the arms 24 and rail extensions 20 being provided with the pins 23 and slots 22 just referred to.

The top rail 25' of the clamp member 25 80 is preferably formed between its ends with an outwardly projected offset 26 with which the clamping means is engaged. This clamping means comprises a horizontal screw 27 swiveled, as indicated at 28, in the 85 offset 26 and engaging in an interiorly threaded sleeve 29 fixed in the rail element, this screw having a head 30 in which is a cross pin 31 for turning purposes. By tightening up the screw 27 the members 10 90 and 25 are clamped upon opposite sides of the window sill and the stand held securely in place.

To form a guard for the person standing on the floor 14 I hinge to the tops of the 95 grooved posts 12, as at 35, a U-shaped frame 36 whose legs 36' align with the posts 12 and are formed with grooves such as 37 aligning with the grooves 18 in the latter. This frame 36 is braced by the sectional tie members 38 connected at opposite ends to the rail element 13 and the top of the frame. These tie members 38 are formed of two bars which engage one another through the medium of pins such as 40 in one bar engaging in longitudinal slots such as 41 in the other bar. This construction enables 100 the guard frame to be folded down on the rail 13.

During such times as it is not in use for 110 washing windows the device is adapted for use as a chair, the parts being then arranged

as shown in Figs. 3 and 4. To convert the device from a stand into a chair, the device is arranged with the clamp member 25 resting on the floor, the rail 13 and frame 11 lying in vertical planes, while the posts 12 are horizontal, the panel 16 providing a seat. The opposite panel 17 is moved from its position between the posts 12 to a position between the legs 36' of the guard frame 36, its edges being held in the grooves 37. The guard frame is swung downwardly to be along the rail 13, the tie members 38 buckling to allow of this movement as will be understood. The frame element 11 has a pair of legs 43 hinged to opposite end parts thereof and which are normally held in position lying along the same by a hook 44. These legs are swung down and rest upon the clamp frame 25, to which they may be secured by a suitable hook 45. The legs 36' of the guard frame 36 are preferably of such a length that the frame will engage the floor when swung down, the chair being thus provided with four legs in addition to that constituted by the screw 27.

Having thus described my invention what I claim as new and desire to protect by Letters Patent of the United States is as follows:—

30 1. A combined chair and window cleaner's stand comprising a box-like member having one side thereof in the form of a removable panel and the opposite adapted to form a seat when the device is in use as a chair, 35 lateral extensions from the last mentioned side of said member adapted to rest on the window sill, and a clamping frame engaged with said extensions and presenting a substantially rectangular portion lying parallel 40 to said last side and of substantially equal area thereto.

2. A combined chair and window cleaner's stand comprising a box-like member having

one side thereof in the form of a removable panel and the opposite adapted to form a seat when the device is in use as a chair, 45 lateral extensions from the last mentioned side of said member adapted to rest on the window sill, and a clamping frame engaged with said extensions and presenting a substantially rectangular portion lying parallel 50 to said last side and of substantially equal area thereto, legs hinged to said last side, and means for securing said legs in position lying in contact with said box-like member 55 or resting at their lower ends on said rectangular portion of the clamping frame.

3. A window cleaner's stand comprising a box-like member, horizontal extensions from the top of said member adapted to rest on 60 the window sill, a clamp frame adapted to engage the window sill, said clamp frame having forward projections from its upper corners said projections having slot and pin connections with the said horizontal extensions, said clamp frame having also a forwardly projected offset between its ends engaging over the window sill, and a clamp screw engaging in said offset and in the said box-like member. 70

4. In a window cleaner's stand, a box-like member, a clamp frame for securing the said member to the window frame, said box-like member having the outer side thereof removable, a guard frame hinged to said box-like member, a pair of legs hinged to said box-like member and opposed to said guard frame, said guard frame and legs being adapted to support the device in position 75 forming a chair.

Signed at borough of Brooklyn, New York city in the county of Kings and State of New York this 4th day of March, A. D. 1921.

JOHN GABRIAL.
